UNITED STATES PATENT OFFICE.

MELVIN C. CLEMONS, OF LOS ANGELES, CALIFORNIA.

HOLDER FOR RULERS AND THE LIKE.

Application filed August 28, 1924. Serial No. 734,651.

To all whom it may concern:

Be it known that I, MELVIN C. CLEMONS, a citizen of the United States, residing at Los Angeles, in the county of Los Angeles and State of California, have invented new and useful Improvements in Holders for Rulers and the like, of which the following is a specification.

This invention relates to devices adapted to retain articles within a pocket upon wearing apparel, and is especially adapted to retain a ruler within a workman's overall pocket.

It is an object of the invention to provide a cheap, simple and durable device adapted to be readily attached to a pocket so as to retain itself therein and which will frictionally and releasably hold an article, such as a ruler within the pocket.

With the foregoing and other objects in view which will be made manifest in the following detailed description and pointed out in the appended claims, reference is had to the accompanying drawings for an illustrative embodiment of the invention, wherein:

Figure 1 is a perspective view of the improved article retaining device,

Fig. 2 is a partial side elevation of a pocket to which the article retaining device has been applied, shown with a ruler inserted in the pocket and retained therein, and

Fig. 3 is a vertical section taken substantially upon the line 3—3 of Fig. 1.

Referring to the accompanying drawings wherein similar reference characters designate similar parts throughout, the article retaining device consists of a single piece of resilient sheet material which may be sheet metal, celluloid, or equivalent material. This sheet is substantially rectangular in form having end portions 10 and 11 which are normally substantially in alignment with each other.

A central portion 12 is bowed out of alignment with the portions 10 and 11, so that normally when the device is placed in an empty pocket, the portion 12 extends across the pocket. A clip 13 is formed upon one end of the sheet of material by bending the end of the sheet back upon itself. A lip 14 extending outwardly away from the end portion 10 is formed upon the clip 13.

As shown in Figs. 2 and 3, the device is

inserted into a pocket with the clip 13 engaging the edge E of the pocket so as to clampingly hold the device therewithin. The outwardly extending lip 14 is preferably provided to facilitate placing the clip 13 upon the edge E. When an article, such as a ruler R, is inserted into the pocket, the bowed portion 12 will be forced outwardly into contact with the outer side S of the pocket and into substantial alignment with the portions 10 and 11. When the portion 12 is in this position as shown in Fig. 3, the portions 10 and 11 press the top and bottom of the side S outwardly and the portion 11 forms a sufficient depression in the side S to retain itself within the pocket.

Because of the resiliency of the material, the bowed portion 12 exerts a considerable force between the side S and the ruler R, thereby frictionally, yet releasably, retaining the ruler R within the pocket which will prevent the ruler from accidentally dropping out of the pocket. Obviously, when it is desired to use the ruler, it may be pulled out of the pocket, overcoming the frictional engagement provided by the portion 12.

Another advantage of the article holding device is that the device will retain the pocket in open position, so that an article, such as the ruler R, may be readily inserted into the pocket. The bowed portion 12 engages the body of the garment and the end portion 10 cooperates with the bowed portion 12 to hold the top of the pocket in spaced relation to the body of the garment.

It will be understood that various changes in the detail of construction may be made without departing from the spirit or scope of the invention as defined by the appended claims.

I claim:

1. A device of the class described comprising a sheet of resilient material adapted to be inserted into a pocket, said sheet being in width approximately equal to the width of the pocket and having a normally inwardly bowed central portion adapted to engage and frictionally maintain an article within the pocket.

2. A device of the class described comprising a sheet of resilient material adapted to be inserted into a pocket, said sheet being in width approximately equal

to the width of the pocket, and means for maintaining said sheet adjacent the outside wall of the pocket, said sheet having an inwardly bowed central portion adapted to engage and frictionally maintain an article within the pocket.

3. A device of the class described comprising a sheet of resilient material adapted to be inserted into a pocket, said sheet having a normally inwardly bowed

central portion and being in width approximately equal to the width of the pocket, and a spring clip formed upon said sheet adapted to engage the upper edge of the outside wall of the pocket so as to maintain said sheet adjacent said outside wall and substantially parallel thereto. 15

In testimony whereof I have signed my name to this specification.

M. C. CLEMONS.
